TIRE

John Tancin, Jr., Freeland, Pa.

Application May 19, 1959, Serial No. 55,978

Term of patent 14 years

(Cl. D90—20)

FIG. 1.

FIG. 2.

FIG. 3.

FIG. 4.

Figure 1 is a perspective view of a tire showing my new design, it being understood that the full line portions of the design are repeated throughout the circumference of the tire shown by means of broken lines;

Figure 2 is an enlarged fragmentary top plan view thereof;

Figure 3 is a longitudinal cross sectional view thereof taken on the line 3—3 of Figure 2; and

Figure 4 is a transverse cross sectional view thereof taken on the line 4—4 of Figure 2.

The dominant features of my design reside in the full line portions of the drawing.

I claim:

The ornamental design for a tire, as shown and described.
